ILLUMINATED DISPLAY DEVICE

Edward A. Willer, Washington, D. C.

Application April 9, 1941, Serial No. 387,739

9 Claims. (Cl. 40—130)

This invention relates to illuminated display devices and is an improvement over my copending application Serial No. 350,749, filed January 30, 1941.

An object of this invention is to provide a device of this kind which may be positioned on the exterior of a building for displaying the number of the building or other indicia, the device including a body element and a cover element, and the latter element being removable for ready placement of number or indicia panels for display purposes.

Another object of this invention is to provide a device of this kind which is so constructed that it may be either stamped out of metal or molded out of plastic composition.

A further object of this invention is to provide in a device of this kind an improved means for holding the number or indicia panels on the body.

A further object of this invention is to provide a device of this kind including an improved means for holding the cover or face of the device on the body or back thereof.

A still further object of this invention is to provide an improved panel for display purposes including means for increasing the luminosity of the number or indicia to be displayed.

A still further object of this invention resides in the new and novel means employed for coupling and supporting an indicia carrying means relative to a light source for the purpose of illuminating the indicia.

Further objects of the invention are to provide, in a manner as hereinafter set forth, an illuminated display device for the purpose referred to which is comparatively simple in its construction and arrangement, strong, durable, compact, pleasing in appearance, thoroughly efficient in its use, readily assembled and comparatively inexpensive to manufacture.

Embodying the objects aforesaid and to others which may hereinafter appear, the invention consists of the novel construction, combination and arrangement of parts as will be more specifically referred to and illustrated in the accompanying drawings, wherein are shown embodiments of the invention, but it is to be understood that changes, variations and modifications may be resorted to which fall within the scope of the invention as claimed.

In the drawings:

Figure 1 is a front elevation of an illuminated display device in accordance with this invention.

Figure 2 is a rear elevation with the cover element removed.

Figure 3 is a section on line 3—3 Figure 1.

Figure 4 is a section on line 4—4 Figure 1.

Figure 5 is a fragmentary detail view in vertical section,

Figure 6 is a vertical sectional view illustrating a modified form of a display component coupling and supporting member arranged relative to the body part of the form shown by 5 Figure 2,

Figure 7 is a perspective view of the form of display component combined coupling and supporting member shown by Figure 6,

Figure 8 is a fragmentary view in front elevation and Figure 9 is a fragmentary view in vertical section of a modified form of body part,

Figure 10 is a sectional plan and Figure 11 is a fragmentary view in rear elevation of another modified form of body part and cover element.

15 Figure 12 is a sectional plan illustrating still another modified form of body part and cover element,

Figure 13 is a fragmentary view in perspective and Figure 14 is a fragmentary view in vertical 20 section of still another modified form of body part,

Figure 15 is a fragmentary view in perspective and Figure 16 is a fragmentary view in vertical 25 section of a modified form of the device for suspension, and

Figure 17 is a fragmentary view in perspective of still another modified form of the device.

Referring to Figures 1 to 5 the device illustrated thereby includes a vertically disposed 30 one-piece body part 20, which is stamped from any suitable metallic material and is so shown. It is to be understood that body part 20 may be molded from any suitable plastic material if desired. The said body part is open at its rear 35 and it includes a front wall 21, a pair of side walls 22, 23, a top wall 24 and a bottom wall 25. The walls 21, 22, 23 and 24 merge into each other. The wall 25 at its front merges into the lower end of and is disposed at a downward inclination with respect to the wall 21. The rear end of wall 25 terminates into a vertically disposed depending extension 26, which at its lower end merges into a forwardly directed flange 27. The walls 22, 23 at their rear merge into a pair 40 of oppositely disposed lateral extensions 28, 29 respectively terminating into forwardly extending flanges 30, 31 respectively. The top wall 24 terminates at its rear into a vertically disposed extension 32 which merges into a forwardly directed flange 33.

The extensions 26, 32 align. The flanges 27, 33 align. The extensions 28, 29 align, and the flanges 30, 31 align. The extensions 28, 29 are formed with openings 34, 35 for the passage of holdfast means to anchor body part 20 to a support, by way of example in proximity to or upon the front door of a building or at any other desired point. The flanges 30, 31 are formed with threaded openings 36 for a purpose to be referred 45 to. The extension 32 is provided with an open-

ing 37 for the passage of holdfast means to anchor such extension against the aforesaid support. The bottom wall 25 is formed with an enlarged opening 40 for a purpose to be referred to and also with a set of spaced slots 39 at its point of jointure with the bottom of wall 21. The top wall 24 is provided with a set of spaced slots 39 at its point of jointure with the upper end of the wall 21. The purpose of the slots 39, 40 will be presently referred to. The walls 22, 23 are slotted, as at 41, and the material freed by said slits is bent forwardly to beyond the sides of the front wall 21 to provide holding tongues 42 for a purpose to be referred to. The slits 41 are at the points of jointure of the side walls with the sides of the front wall. The forward face of the latter is formed with an opaque coating 42.

Encompassing the body part 20 is a cover element 43 of frame-like form consisting of a front portion 44 formed with an opening 45 having its 20 edge provided with an endless rearwardly directed spacing bead or rib 46, side portions 47, 48, a top portion 49 and a bottom portion 50. Each of the side, top and bottom portions consists of an outwardly directed rearwardly extending curved 25 forward part 51 merging into a straight rearwardly directed back part 52. The element 43 is of one-piece and may be stamped from metallic material or molded from any suitable plastic, but it is shown by way of example as stamped from 30 a single length of sheet metal. The manner in which the element 43 is arranged relative to body part 20 will be hereinafter more specifically referred to.

The rear parts 52 of the said side portions 47, 35 48 are formed with openings 53 and such parts are positioned against the outer faces of the flanges 30, 31, which are connected with the said side walls 22, 23. The openings 53 register with the openings 36. The rear part 52 of the said top portion 49 is positioned against the outer face of the flange 33, which is connected with the top wall 24. The rear part 52 of the said bottom portion 50 is positioned against the lower face of the flange 27 connected with the said bottom wall 25. Correlating with the registering openings 36, 53 are attaching means 54 for detachably securing the element 43 to the body part 20. The cover element, if constructed of sheet metal, will be of a size to be snapped about the body part 20 and to frictionally engage the flanges aforesaid.

The lower part of the said front portion 44, the lower part of the said side portions 47, 48, the said bottom portion 50, the said inclined bottom 55 wall 25, the said extension 26 and flange 27 are so correlated to form a chamber 55 for an electric lamp 56, which is extended into such chamber through an opening 57 formed in the wall 25. The latter is provided with an apertured lug 58 60 for carrying a holding or suspension means 59 for and which engages the lamp 56. The said bottom wall 25 forms the top wall of the chamber 55. The lower part of the said front portion 44 and the part 51 of the said bottom portion 50 of the 65 element 43 form the front wall of the chamber 55. The top wall of chamber 55 is spaced rearwardly from the upper end of the front wall of such chamber to provide a light emitting passage 60. The chamber 55 is closed at its front, 70 sides, bottom and back. The walls of the chamber 55 are formed throughout with a coating 60^a constituting a reflecting surface and by way of example said coating may be white paint or white enamel.

5 The device includes a display carrying means for any suitable indicia. The latter is shown by way of example as designating a house number. The said means will be formed of a plurality of components, and by way of example is illustrated as consisting of four components 61, 62, 63 and 64 arranged at the rear of the front portion 44 of element 43 and at the front of the wall 21 of body part 20 between the tongues 42 extended from the side walls 22, 23 of body part 20. In the example of the invention as shown each component consists of a rectangular transparent panel 65 preferably formed of glass provided on its rear face with a digit or an ough. Preferably the digits and oughs will be white and are painted on the rear faces of the panels. As shown, the panel 65 of the component 61 has a digit 66 on its rear face which indicates "one"; the panel 65 of the component 62 has a digit 67 on its rear face, which indicates "two"; the panel 65 of component 63 has an ough 68 on its rear face; and the panel 65 of component 64 has a digit 69 on its rear face which indicates "four." The example as aforesaid will indicate the house number as "1204." Preferably the panels of the components will be of the desired size and also correspond in size. The panel of each component is adapted to be illuminated from an edge thereof and that edge of the component opposite the edge which the light enters is provided with a white coating. In the example of the invention as shown the said coating is indicated at 69^a and it is throughout the top edge of the panel.

25 There is correlated with each component of the display carrying means a combined supporting and coupling member 70 therefor. These members are of like form and each consists of a rod of circular cross section formed of a straight intermediate portion 71, an upper end portion 72 constituting a coupler and a lower end portion 73 providing a support. The end portions 72, 73 are angularly disposed with respect to and extend forwardly from the ends of the intermediate portion 71. The upper end portion 72 is of hook form, and the lower end portion 73 straight.

40 The members 70 are removably mounted in and supported from the body part 20 and when mounted relative to the latter each couples a component of the display carrying means to body part 20 and also supports the component. The latter when coupled to and supported in relation to body part 20 is arranged in juxtaposition to the forward face of the front wall 21 of the said body part.

45 The intermediate portions 71 of the members 70 are arranged rearwardly of and in proximity to the rear face of the front wall 21 of body part 20; the upper end portions 72 of the members 70 extend through the slots 39, pass over the upper end of wall 21 and overlap the top edges of the said components; and the lower end portions 73 of the members 70 extend through the slots 40, pass under the lower end of wall 21 and bear against the bottom edges of the said components. This arrangement provides for not only supporting the said components relative to body part 20, but also couples the components to said body part. The members 70 are disposed centrally with respect to the said components and arranged in parallel spaced relation. When the components are supported and coupled relative to the body part 20 the bead 46 on the front portion 44 of the element 43 bears against the front faces of and acts as a retaining means for holding the components against the wall 21 of body part 20.

The bead 46 at its top is arranged below the outer termini of the end portions 72 of the members 70. The bead 46 at its bottom is arranged above the outer termini of the end portions 73 of the members 70. The end portions 72 are of greater length than the end portions 73.

The leading-in-wires for the lamp 56 are indicated at 74.

The manner of installing the components of the display means relative to the body part 20, cover element 43 and lamp 56 provides for the illumination of the said components from their bottom edges, as such edges are positioned in the opening 60 formed in the top of the lamp chamber 55. The opposing of an opaque background by the white indicia on the rear faces of the transparent panels will provide for such indicia to be readily visible by day and also when the components are illuminated at night.

With reference to Figures 6 and 7 the construction shown thereby will correspond to that shown by Figures 1 to 5, with this exception that the combined supporting and coupling member indicated at 75 will be flat and rectangular in transverse cross section in lieu of its being rounded and of circular cross section. The intermediate part, upper end hook-shaped coupling part and lower end flat supporting part of member 75 are indicated at 76, 77 and 78 respectively. The end portion 77 is of greater length than the end portion 78.

The modified form illustrated by Figures 8 and 9 relates solely to the body part 79 of the device. The body part 79 is so formed as to have inherent parts thereof constitute means for coupling thereto and supporting therefrom the components of the display carrying means instead of using the members 70 or 75. The body part 79 will include front, top, bottom and side walls, but only one of the side walls is shown and indicated at 80. The front, top and bottom walls of body part 79 are indicated at 81, 82, 83 respectively. The front face of wall 81 will have an opaque coating the same as the front wall 21 of body part 20. The top wall 82 is formed with a series of spaced slits 84, only one shown, and the material freed by each slit is bent forwardly to extend beyond the wall 81 to provide a coupler 85 for a display component. The coupler 85 is of hook-like form and overlaps the top of display components (Figures 8 and 9) for coupling the latter to body part 79. The bottom wall 83 is formed with a series of spaced slits 86, only one shown, and the material freed by each slit 86 is bent forwardly to extend beyond the front wall 81 to form a flat support 87 for the bottom edge of a display component (Figures 8 and 9). Otherwise than that as stated the modified construction shown by Figures 8 and 9 will be the same as that illustrated by Figures 1 to 5 or 6 and 7.

The form of the device shown by Figures 10 and 11 will be the same as that shown by Figures 1 to 5 with the addition of a latching flange 88, which extends inwardly at right angles to the rear part 52 of one of the side portions of the cover element 43. The flange 88 is spaced from the upper and lower ends of such portion and it is for snapping against the rear face of the extension 28 on a side wall of the body part of the device. A further difference between the form shown by Figures 10 and 11 and the form illustrated by Figures 1 to 5 resides in not providing that part 52 formed with the flange 88 with an opening 36 or securing such part 52 by a holdfast means 54 to the flange 30. Otherwise than

that as stated the form shown by Figures 10 and 11 will be the same as that illustrated by Figures 1 to 5.

With reference to Figure 12, the modified form shown thereby includes a body part 89 and a cover element 90. The body part 89 is similar to body part 20 with the exception that the flanges 91, 92 connected with the side walls 93, 94 respectively of the body part 89 are not formed with openings 36 as the flanges 30, 31 of the side walls 22, 23, and that the flange 91 is formed with a detent 95 having its concave side outermost. The cover element 90 is similar to cover element 43 with the exception that the rear part 96 of the side portion 97 of element 90 is not apertured as is the side portion 47 of element 43 and such part 96 is formed with a detent 98 having its convex side innermost for correlation with the detent 95 for latching element 90 to body part 89 by a snapping action. A further difference between the element 90 and the element 43 resides in the providing of the rear part 99 of side portion 100 of element 90 with an inwardly extending flange 101 for abutting the rear face of the extension 101a on the side wall 94. Otherwise than that as stated the form shown by Figure 12 is to conform to the construction of the device shown by Figures 1 to 5.

With reference to Figures 13 and 14 there is illustrated still another modified form of body part which is molded from plastic material. Such body part is indicated at 102 and includes flanged top, side, front and bottom walls of the same form as the walls of body part 20, with this exception that top wall 103 and bottom wall 104 of body part 102 are not slotted or formed with openings and that the side walls 105 of body part 102 merge at their lower ends into the bottom wall 104. A further difference between body part 102 and body part 20 resides in forming the upper face of the top wall 103 with integral spaced parallel pairs of spaced oppositely disposed inverted L-shaped members 106, which are flush at their forward ends with the front face of the front wall 107 of body part 102. Only one pair of the members 106 is shown and each pair of said members constitutes a holder for a resilient coupler 108 of hook-like form for a display component 108a. The couplers 108 will be of like form and each includes a shank having a part 109 bearing against the inner face of the top of the holder and a bow-shaped part 110 bearing against the upper face of said top wall 103. The shank of the coupler coacts with a pair of members 106 and the top wall 103 for latching the coupler 108 to body part 102. Another difference between body part 102 and body part 20 resides in the providing of the outer faces of the side walls 105 with integral forwardly directed lugs 111, only one shown, which extend beyond the front wall 107 and function for the same purpose as the tongues 42 of body part 20. A further difference between the body part 102 and the body part 20 resides in the providing of the bottom of the front wall 107 with spaced parallel integral forwardly directed lugs 112, only one shown. The lugs 112 align with the couplers 108 and each constitutes a support for the bottom edge of a display component. Otherwise than as stated the construction of the body part 102 will conform to body part 20.

With reference to Figures 15 and 16, a modification of the device is shown and it is formed so as to permit of it being attached at its top to a suspension 113. The device as illustrated by

Figures 15 and 16 may be formed from metallic or plastic material, and it includes a body part 114 and a cover element 115. The body part 114 will be substantially of a form corresponding to that of body part 20 with the exception that the top wall 116 thereof is formed with an opening 117 for the passage of the leading-in-wires 118 to the lamp arranged in the lamp chamber. The lamp and its chamber are not shown in Figures 15 and 16. A further difference between body part 114 and body part 20 is the forming of the flange 119, which is connected with the top wall 116, with a cutout 120 for the passage of the wires 118.

The cover element 115 shown by Figures 15 and 16 is constructed similar to the cover element 43, with the following differences. That the rear part 121 of the top portion 122 of element 115 is formed with an opening 123 for the passage of the wires 118; that the upper face of the said part 121 is formed with a concave recess 124 rearwardly of the opening 123; and that the said top portion 122 has integral therewith a vertically disposed apertured lug 125 to which the suspension 113 is attached. The coupling and supporting means for a display component employed in the form of the device shown by Figures 15 and 16 may be similar to that of Figures 1 to 6 or that shown by Figures 13 and 14. The device as illustrated by Figures 15 and 16 includes a rim-like closure 126 for the back of body part 114 and element 115. The closure 126 has its rim portion 127 encompassing the rear of the element 115. The said portion 127 includes a lug 128 for snapping in the recess 124 whereby the closure 126 will be latched to element 115. Otherwise than that as stated the form illustrated by Figures 15 and 16 will correspond in construction to the form shown by Figures 1 to 5.

With reference to Figure 17 there is shown a modified form of closure 129 for the back of the body part 130 and closure element 131 of the device. The element 131 will correspond in structural arrangement to the element 43. The body part 130 will be similar to the body part 20 with this exception that the extension 132 on the top wall 133 is formed with one or more threaded openings 134, only one shown. The closure 129 is in the form of a flat plate 135 which abuts against the back of body part 130 and element 43, and it is detachably secured in such position by the holdfast means 136 extending through the plate 135 and engaging in an opening 134. When the device shown by Figure 17 is set up the openings 34, 35 (Figure 2) preferably will be omitted.

It is to be understood that the front face of the front wall of any one of the body parts will be provided with an opaque coating and that each display component will have an edge formed with a white coating as referred to.

The components of the display means are to be arranged against the opaque front face of the front wall of a body part. Each component is positioned separately, after which it is coupled and supported relative to and in juxtaposition to such wall by a member 70 or 75, or by a coupler 108 and a lug 112. The component or panel when positioned as aforesaid has its lower portion extended into the opening 60 to a point below the lower portion of the bead 46. After the desired number of display components or panels are arranged in the manner as aforesaid the body part of the device is encompassed by a cover element and the latter is then latched or secured to the

body part. When the cover element is secured to the body part the display carrier means extends above the top portion of the bead 46 and also extends laterally from the side portions of the bead 46. It will be stated that the indicia on the panels will be displayed through the opening 45 in the front portion 44 of a cover element. When the display carrier means is arranged in position the upper, lower and side marginal portions of its front face will be overlapped by the front portion of the cover element, and when in such position the bead 46 will bear against such means and in connection with the coupling and supporting means hold said display carrying means in vertical position for displaying the indicia.

The panels of the display carrying means are arranged in sidewise abutting relation and are held in such position by the tongues 42 or lugs 111. The panels of the display carrying means may be readily removed after the cover element is removed or when the closure 129 is detached from the cover element and the latter removed from the body part of the device.

At night the display carrying means is illuminated from its bottom edge by the lamp 56. It is to be understood that the leading-in-wires are to be provided with a switch and also a plug for connection to an electrical output. It is thought unnecessary to show this arrangement as it is common.

What I claim is:

1. In an illuminated display device, a hollow body part having a front wall, said wall having its outer face provided throughout with an opaque coating, a transparent body having white display indicia on one face opposing said opaque coating, means for coupling and supporting said transparent body relative to and forwardly of said front wall, said transparent body being disposed for illumination from an edge thereof and being provided with a white coating on an edge thereof opposite the edge from which said transparent body is illuminated, means having an exposure opening for said indicia and for retaining said transparent body against said wall, and means for illuminating said transparent body.

2. In an illuminated display device, a hollow body part having a front wall, said wall having its outer face provided throughout with an opaque coating, a transparent body having white display indicia on one face opposing said opaque coating, means for coupling and supporting said transparent body relative to and forwardly of said front wall, said transparent body being disposed for illumination from an edge thereof and being provided with a white coating on an edge thereof opposite the edge from which said transparent body is illuminated, means having an exposure opening for said indicia and for retaining said transparent body against said wall, said last mentioned means and said hollow body part having coating portions to provide a chamber adjacent said wall, an illuminating element in said chamber, and said chamber having a light emitting opening to provide for the illuminating of said transparent body from an edge of the latter.

3. In an illuminated display device, a hollow body part having a front wall, said wall having its outer face provided throughout with an opaque coating, a transparent body having white display indicia on one face opposing said opaque coating, means for coupling and supporting said transparent body relative to and forwardly of

said front wall, said transparent body being disposed for illumination from an edge thereof and being provided with a white coating on an edge thereof opposite the edge from which said transparent body is illuminated, means having an exposure opening for said indicia and for retaining said transparent body against said wall, means for illuminating said transparent body, and said hollow body part being provided with spaced parallel tongues to arrest lateral shifting of said transparent body when the latter is coupled to and supported relatively to said front wall.

4. In an illuminated display device, a hollow body part having a front wall, said wall having its outer face provided throughout with an opaque coating, a transparent body having white display indicia on one face opposing said opaque coating, means for coupling and supporting said transparent body relative to and forwardly of said front wall, said transparent body being disposed for illumination from an edge thereof and being provided with a white coating on an edge thereof opposite the edge from which said transparent body is illuminated, means having an exposure opening for said indicia and for retaining said transparent body against said wall, said last mentioned means and said hollow body part having coating portions to provide a chamber adjacent said wall, an illuminating element in said chamber, said chamber having a light emitting opening to provide for the illumination of said hollow body from an edge of the latter, and said hollow body part being provided with spaced parallel tongues to arrest lateral shifting of said transparent body when the latter is coupled to and supported relatively to said front wall.

5. In an illuminable display device having a display carrying means; a hollow body part including a front wall, a flanged top wall, flanged side walls and a flanged bottom wall inclining downwardly from said front wall, a cover element of frame-like form encompassing and detachably connected to said body part, said element engaging the flanges of said top, bottom and side walls and including an open front portion and top, bottom and side portions, spaced means for coupling and supporting said carrying means relatively to and forwardly of said front wall and rearwardly of the front portion of said element, said element having the lower parts of its side portion and the lower part of its front portion correlating with said bottom wall to provide a chamber for receiving an illuminating element for the supported display carrying means, said chamber having an opening for the extending therein of said display carrying means.

6. In an illuminated display device having a display carrying means; a hollow body part including a front wall, a flanged top wall, flanged side walls and a flanged bottom wall inclining downwardly from said front wall, a cover element of frame-like form encompassing and detachably connected to said body part, said element engaging the flanges of said top, bottom and side walls and including an open front portion and top, bottom and side portions, spaced means for coupling and supporting said carrying means relatively to and forwardly of said front wall and rearwardly of the front portion of said element, said element having the lower parts of its side portions and the lower part of its front portion correlating with said bottom wall to pro-

vide a chamber for receiving an illuminating element for the supported display carrying means, said chamber having an opening for the extending therein of said display carrying means, and said body part being provided with spaced parallel tongues to arrest lateral shifting of the display carrying means when the latter is coupled to and supported relative to said front wall.

7. In an illuminated display device, a hollow body part having a front wall, said wall having its outer face provided throughout with an opaque coating, a transparent body having white display indicia on one face opposing said opaque coating, means for coupling and supporting said transparent body relative to and forwardly of said front wall, said means including an elongated member having a forwardly extended lower end portion engageable beneath said transparent body and a forwardly extending upper hook portion engageable over the upper edge of said transparent body, said hollow body being provided with openings through which the extended portions of said members engage, said transparent body being disposed for illumination from an edge thereof opposite the edge from which said transparent body is illuminated, means having an exposure opening for said indicia and for retaining said transparent body against said wall, and means for illuminating said transparent body.

8. In an illuminated display device, a hollow body part having a front wall, said wall having its outer face provided throughout with an opaque coating, a transparent body having white display indicia on one face opposing said opaque coating, means for coupling and supporting said transparent body relative to and forwardly of said front wall, said means including a forwardly projecting transparent body supporting lug carried by the lower portion of the front wall of said hollow body, a resilient coupler engageable over the upper edge of said transparent body, and a holder for said coupler carried by the upper portion of said transparent body, said transparent body being disposed for illumination from an edge thereof and being provided with a white coating on an edge thereof opposite the edge from which said transparent body is illuminated, means having an exposure opening for said indicia and for retaining said transparent body against said wall, and means for illuminating said transparent body.

9. In an illuminated display device, a hollow body part having a front wall, said wall having its outer face provided throughout with an opaque coating, a transparent body having white display indicia on one face opposing said opaque coating, means for coupling and supporting said transparent body relative to and forwardly of said front wall, said transparent body being disposed for illumination from an edge thereof, and being provided with a white coating on an edge thereof opposite the edge from which said transparent body is illuminated, means having exposure openings for said indicia and for retaining said transparent body against said wall, said means including a cover element formed with an inwardly extending lug engageable over the back portion of said hollow body part and means correlated with said lug for detachably securing said cover to said hollow body, and means for illuminating said transparent body.

EDWARD A. WILLER.
